UNITED STATES PATENT OFFICE.

JOSEPH W. PHINNEY, OF BOSTON, MASS., ASSIGNOR TO GEORGE J. PIERCE,
ALEXR. PHEMISTER, AND ALFRED C. CONVERSE, OF SAME PLACE.

DESIGN FOR PRINTING-TYPE.

SPECIFICATION forming part of Design No. 13,328, dated October 3, 1882.

Application filed June 5, 1882. Term of patent 7 years.

To all whom it may concern:

Be it known that I, JOSEPH WARREN PHINNEY, a citizen of the United States, residing at Boston, in the county of Suffolk and State of Massachusetts, have invented and produced a new and original Design for Printing-Types, of which the following is a specification, reference being had to the accompanying representation.

10 The description of my new type is as follows: The type are capitals, and the name I give the style is the "Æsthetic." In respect to the large capitals, the chief character of the ornamentation, added to the simple letter, is, first, a circle 15 with spots within it, and considered to resemble a sunflower; second, a curved line bearing at its end a half-circle, formed by radiating, curved, bulb-shaped lines, like the petals of a flower, and considered to resemble a lily; third, 20 a scroll or flourish resembling a tendril or a helical screw, viewed from above; and, fourth, a dot connected with the letter by a curved line. These four figures are used in varying 25 combinations to the extent of one or more on each of the letters, and are variously disposed as to superposition and in other ways as to their respective locations, (as a sunflower and a lily, a lily and a tendril, a sunflower and a tendril, or a tendril and a dot.) The letters are 30 block letters, the horizontal and other lines being mostly of the same width as the upright lines. The alphabet has two A's, two E's, two H's, two K's, two M's, two U's, two W's, and two Y's, the supernumerary letters resembling 35 the Old English style. The letters A, the Old

English H, one of the M's, the tail of the Q, and the Y have one downward line brought below the general line of the character and then curved upward with a waved termination. This waved termination to lines is also seen in the upper horizontal line of the F, the lower part of the S, the horizontal line of the T, and the Old English U. The D has the upright line not reaching quite to the horizontal line above. The A, (one,) the D, the J, the Old English H, 40 and one of the K's have a dot and a thin curved line at one end of their upper lines. A similar dot and line is attached below to the ceriph of the G, the right-hand vertical line of the regular H, the lower diagonal line of the regular 45 K, the left-hand vertical line of the N, and the diagonal lower line of the R and &, the dots being below the general line of the letters. Some other but inconsiderable changes from the normal form of the plain block capital are 50 also seen in the Æsthetic type and best apprehended through inspection of the drawing hereto attached.

The drawing appended is referred to for a more exact definition of the appearance of the 55 numerals. Three characters of ornamental forms and circular shape seen in the drawing are used as terminal characters.

I claim—

The design for printing-types herewith presented, substantially as described and shown.

JOSEPH WARREN PHINNEY.
